The ornamental design for a spoon with dorsal prongs, as shown and described.

DESCRIPTION

FIG. 1 is a perspective view showing my new design, where prongs project from a dorsal side of a utensil bowl of the spoon;

FIG. 2 is a bottom plan view thereof;

FIG. 3 is a top plan view thereof;

FIG. 4 is a left side plan view thereof;

FIG. 5 is a right side plan view thereof;

FIG. 6 is an end-on view as seen looking down the utensil bowl of the spoon thereof; and,

FIG. 7 is an end-on view as seen looking down a handle that is continuous with the utensil bowl of the spoon thereof.
